[57] ABSTRACT

A sheet of plastic film having a message printed thereon is stretched across the center opening of two concentric rings. The sheet passes between the mating surfaces of the rings which are held in the opening in the center of a tire. The outer ring includes a flange that engages the exterior surface of the side wall of the tire, and the inner ring includes several lugs that engage the inner periphery of the wall. The mating surfaces of the rings are provided with recesses and projections that engage each other to hold the inner and outer rings together.

TIRE CENTER DISPLAY APPARATUS

BACKGROUND OF THE INVENTION

This invention relates to a display apparatus, and more particularly to a new and highly improved apparatus for displaying a message in the center of a tire.

It is recognized by the advertising industry that some advertising messages, particularly messages relating to automobile tires, can be most effectively presented if the message can be held in the center of a tire so that the tire not only provides a supporting function but also contributes to the appearance and visual effectiveness of the display. This arrangement has been found to be attention-getting as well as attractive. It conveniently directs the attention of the viewer to the tire which is, in most instances, the subject of the displayed message.

Because tires are marketed at a large number of widely separated locations, such as gasoline and service stations, it is important that the message be held in the display position by an apparatus which is simple, very inexpensive, and easily packaged for shipping. It should be light in weight, long lasting, and easily assembled and disassembled by unskilled persons.

In the past, apparatus for holding a display in the center of a tire have, for the most part, consisted of relatively elaborate and complex structures made of wire that hold a rigid cardboard disk. The wire is relatively heavy, and therefore expensive to ship. It is easily bent out of shape and relatively expensive to manufacture. Moreover, the cardboard does not maintain an attractive appearance for the desired length of time. Accordingly, there is a recognized need for an improved apparatus to perform this task.

SUMMARY OF THE INVENTION

The present invention consists of a greatly improved apparatus for displaying a message in the center of a tire. It comprises an inner ring and an outer ring. The outer ring has a slightly larger diameter. A means for engaging the inside of the inner periphery of the wall of a tire extends outwardly from one edge of the inner ring. The outer ring includes a flange extending outwardly from one edge thereof to engage the exterior surface of a wall of the tire. The apparatus includes means for holding the inner and outer rings in concentric engagement with each other.

The two rings are used in combination with a flexible sheet of plastic material on which a message is printed. This sheet is stretched across the center of the two rings and passes between their mating surfaces whereby it is securely held in position. The tire which is engaged by the rings also forms part of the combination.

The means for holding the two rings in engagement with each other may comprise one or more projections on one of the mating surfaces of the two rings and one or more recesses on the opposite mating surface. The means for engaging the inner surface of the inner periphery of the tire wall may comprise at least three lugs extending at right angles from the inner ring. The rings may be made of plastic which, although sufficiently rigid to hold the flexible sheet securely, is deformable to provide for engagement and disengagement of the means for holding the rings together.

BRIEF DESCRIPTION OF THE DRAWINGS

For a more complete understanding of the invention, reference may be had to the following detailed description taken in conjunction with the accompanying figures of the drawings in which:

FIG. 1 is a three-dimensional exploded view of a display apparatus constructed in accordance with the invention;

FIG. 2 is a front view of the apparatus of FIG. 1 assembled in combination with a tire; and

FIG. 3 is a fragmented cross-sectional view of the combination of FIG. 2.

DESCRIPTION OF AN EXEMPLARY EMBODIMENT

An apparatus for supporting and displaying a flexible sheet of message bearing material across the opening in the center of a tire includes, in the preferred form described here, two plastic rings 10 and 12. The inner ring 10 includes three lugs 14 extending at right angles from its lower edge 16. The outer ring 12 includes a flange 18 extending outwardly from its upper edge.

One of the rings 10 includes a plurality of ridge like projections 20 disposed about the surface of its outer periphery 22. The outer ring 12 includes a recess 24 disposed about its inner periphery 26.

When the apparatus is assembled, a thin flexible sheet of plastic film 28 having a message printed thereon is placed over the center opening of the inner ring 10. The outer ring 12, which is of slightly larger diameter than the inner ring 10, is then placed over the inner ring 10 and the flexible sheet 28. The projections 20 engage the recess 24 to form a means for holding the mating surfaces 22 and 26 of the two rings in engagement with each other. The flexible sheet 28 is stretched across the center opening defined by a flange 30 extending inwardly from the top of the ring 10. The rings 10 and 12 are made of substantially rigid plastic but are sufficiently deformable to permit the rings to be engaged and disengaged.

The assembly apparatus including the flexible sheet 28, is attached to a conventional tire 32 of the type used for automobiles. The message printed on the sheet 28 appears across the center opening of the tire as shown in FIG. 2. If the sheet 28 is made of transparent material, the message will appear to be suspended within the center opening of the tire giving the display a particularly pleasing and attention-getting appearance.

The assembled apparatus is shown in greater detail in the fragmentary sectional view of FIG. 3. Here it can be seen that the lugs 14 are provided with hook like projections 34 on their outer ends to securely engage the inside of the inner periphery of a side wall of the tire 32. Two lugs 14 would be sufficient to retain the rings, but three or more are preferred. The flange 18 engages the exterior surface of the wall of the tire 32 so that the rings are securely attached to the tires. The flange 18 and the lugs 14 may be dimensioned so that tires having more than one size of center opening can be used in combination with the rings.

As will be apparent to those skilled in the art, the embodiment described above is meant to be exemplary and it is susceptible to modification and variation without departing from the spirit and scope of the in-

vention. For instance, the means for engaging the exterior surface of the walls of the tire could comprise a plurality of separate projections instead of the disclosed flange 18, or a means different from the projections 20 and recess 24 could be used to maintain the rings 10 and 12 in concentric relation. Therefore, the invention is not meant to be limited except as defined by the appended claims.

I claim:

1. An apparatus for supporting and displaying a flexible sheet of message bearing material across the opening in the center of a tire comprising an inner ring and an outer ring, the inner ring including means extending from one edge thereof for engaging the inside of the inner periphery of the side wall of the tire, and means disposed about the outer periphery thereof for engaging the inner periphery of the outer ring, the outer ring being of larger diameter than the inner ring and including at least one projection extending from an edge thereof to engage the exterior surface of the side wall, and means disposed about the inner periphery of the outer ring for engaging the outer periphery of the inner ring.

2. The apparatus of claim 1 wherein the inner and outer rings are made of deformable plastic.

3. The apparatus of claim 1 wherein the means for engaging the inside of the inner periphery of the side wall comprises at least two lugs extending at right angles from the inner ring.

4. An apparatus for supporting and displaying a flexible sheet of message bearing material across the opening in the center of a tire comprising an inner ring made of deformable plastic including means extending from

one edge thereof for engaging the inside of the inner periphery of a side wall of the tire, an outer ring made of plastic, having a larger diameter than the inner ring and including a flange extending from one edge thereof to engage the exterior surface of a side wall of the tire, and means for holding the inner and outer rings in concentric engagement with each other.

5. The apparatus of claim 4 wherein the means for holding the inner and outer rings in engagement with each other comprises at least one projection and at least one cooperating recess formed on the mating surfaces of the two rings, whereby the flexible sheet can be securely held stretched across the center of the rings with a portion of the sheet passing between the mating surfaces of the rings.

6. The apparatus of claim 4 wherein the means for engaging the inside of the inner periphery of the side wall comprises at least two lugs extending at right angles from the inner ring.

7. A display apparatus comprising a tire, a flexible sheet of plastic film having a message printed thereon, a plastic inner ring having at least three lugs extending from one edge thereof and engaging the inner periphery of a side wall of the tire, an outer plastic ring of larger diameter than the inner ring arranged in concentric relation with the inner ring having a flange extending from one edge thereof to engage the exterior surface of the side wall, and means for holding the mating surfaces of the inner and outer rings in engagement with each other, the sheet of flexible material being stretched across the center of the rings and passing between the mating surfaces of the rings.
